UNITED STATES PATENT OFFICE.

FRANS G. ALBORN, OF MILFORD, CONNECTICUT, ASSIGNOR, BY MESNE ASSIGNMENTS,
TO THE LOCOMOBILE COMPANY, OF BRIDGEPORT, CONNECTICUT, A CORPORATION
OF DELAWARE.

TAPPET-VALVE MECHANISM.

1,399,839.

Specification of Letters Patent. Patented Dec. 13, 1921.

Application filed August 16, 1918. Serial No. 250,143.

To all whom it may concern:

Be it known that I, FRANS G. ALBORN, a citizen of the United States, and resident of Milford, in the county of New Haven, 5 State of Connecticut, have invented an Improvement in Tappet-Valve Mechanisms, of which the following description, in connection with the accompanying drawings, is a specification, like characters on the drawings representing like parts.

This invention relates to tappet valve mechanisms of the class in which the tappet or valve lifter is free to rotate in its guide and is usually not only reciprocated by a 15 cam but rotated thereby to distribute the wear on that end of the tappet which serves as a wiper coöperating with the cam. My invention is more particularly concerned with means for facilitating the axial 20 adjustment of the tappet with relation to the valve.

My invention will be best understood by reference to the following description when taken in connection with the accompanying 25 drawings of one specific embodiment thereof, while its scope will be more particularly pointed out in the appended claims.

In the drawings:

Figure 1 is a vertical sectional view of a 30 portion of an internal combustion engine having a tappet valve mechanism embodying my invention;

Fig. 2 is a sectional view on line 2—2 of Fig. 1; and

Fig. 3 is a sectional view on line 3—3 of Fig. 1.

Referring to the drawings and to the embodiment of my invention which is illustrated therein, I have shown for purposes 40 of exemplification a portion of a common form of internal combustion engine having a tappet valve mechanism whose general features are well known to those skilled in the art. The typical valve mechanism 45 shown herein comprises a puppet valve 4 coöperating with a valve seat 5 and provided with a stem 6 guided by a valve stem guide 7 and normally seated by a spring 8, the latter resting against one end at a fixed 50 abutment 9 and at its other end against an abutment 10 carried by the valve stem.

The valve actuating mechanism comprises a usual cam shaft 11 having thereon a cam 12 which coöperates with a valve lifter or 55 tappet 13, the latter being guided by a valve

lifter guide 14 which in the example shown is secured in the crank case a portion of which is shown at 15, the fastening means selected for exemplification being a usual clamping yoke 16 and stud 17 having a nut 60 18. Preferably the axis of the tappet or valve lifter 13 is offset with relation to the cam 12, as clearly shown in Fig. 1, the effect being to cause the tappet to be rotated about its axis in a manner well known to those 65 skilled in the art. This distributes the wear by rotating the tappet slightly from time to time as it reciprocates.

As is well known in valve mechanisms of this class, an accurate adjustment is required between the valve and the tappet in order that the valve may at all times seat properly, yet without undue noise. It is usually customary to provide a means of adjustment whereby a clearance space of 70 from three to five thousandths of an inch is maintained between the coöperating end faces of the valve stem and the tappet. Such means of adjustment usually comprises a cap screw 19 threaded into the upper end 80 of the tappet whereby the latter, in effect, may be lengthened or shortened at will. A lock nut 20 threaded onto the adjusting screw is provided to maintain the proper adjustment of the latter in the usual manner. It has heretofore been customary to provide the tappet with flat faces 21 to which a wrench may be applied to hold the tappet against rotation while the adjustment 85 is being made. It has heretofore been impossible to accomplish this adjustment in an accurate and satisfactory manner by the use of two hands because it is really necessary to apply a wrench to the adjusting screw, another to the lock nut and another 90 to the tappet, so that the latter can be held against rotation while the screw and lock nut are rotated to obtain the proper adjustment and then secure the parts in such 95 position.

In order to enable one person to accomplish the adjustment readily, I have provided means for temporarily locking the tappet against rotation so that the workman 100 may then manipulate the screw by means of a wrench held in one hand and the nut by a wrench held in the other. To this end I may provide the tappet guide 14 with a suitable opening to receive a suitable locking element coöperating with the valve lifter or 110

tappet. In the present embodiment of my invention this opening is in the form of a wide and rather shallow groove 22 milled, planed or otherwise formed across the upper end of the guide 14. This forms a pair of flat faces 23 to which the flat faces 21 of the tappet may be opposed by turning the latter until one set of faces is approximately parallel to the other. I may then introduce between the opposed faces a suitable locking element which will hold the tappet against rotation during the adjustment but may afterward be removed, thus freeing the tappet and allowing the latter to be rotated in the usual manner. By providing a groove which is open at the upper end of the tappet guide, no harm can result to the mechanism if the workman should inadvertently leave the locking element in place since such element would simply rise and fall with the tappet, the only difference being that the latter would not rotate.

The locking element may take various forms but in the present embodiment of my invention I have shown a generally U-shaped key 24 having a pair of arms 25 of suitable size and shape to slide into the spaces between the opposed faces 21 and 23, as clearly shown in Figs. 1 and 2. When this is done the tappet is temporarily but none the less securely locked against rotation and the workman may then proceed with the making of the adjustment without giving the key further thought until the adjustment is completed, whereupon the key may be withdrawn. As before stated, however, should the workman forget to remove the key no real harm can result.

Having thus described one form or embodiment of my invention, what I claim and desire to secure by Letters Patent is:—

1. In a tappet valve-actuating mechanism of the class in which the tappet rotates and reciprocates, the combination of a tappet having a screw and nut for effecting axial adjustment and means coöperating with a fixed part of the mechanism to lock said tappet against rotation in opposite directions preparatory to making such adjustment.

2. In a tappet valve-actuating mechanism of the class in which the tappet rotates and reciprocates, the combination of a tappet having a screw and nut for effecting axial adjustment, a guide in which said tappet reciprocates and is normally free to turn, and means coöperating with said guide to lock said tappet against rotation preparatory to making such adjustment.

3. In a tappet valve-actuating mechanism of the class in which the tappet is cam-actuated and is normally free to rotate, the combination of a tappet having rotatable means for effecting axial adjustment, a guide in which said tappet reciprocates and is normally free to turn, and means adapted to

interlock with said guide and tappet to lock the latter against rotation preparatory to making such adjustment.

4. A valve mechanism, comprising in combination, a puppet valve, a valve-lifting cam, a normally rotatable valve-lifter actuated by said cam, rotatable adjusting means carried by said valve-lifter, and means coöperating with a fixed part of the mechanism to lock said valve-lifter against rotation in opposite directions.

5. A valve mechanism comprising, in combination, a puppet valve, a valve-lifting cam, a normally rotatable valve-lifter actuated by said cam, rotatable adjusting means carried by said valve-lifter, and a valve-lifter guide, said valve-lifter and guide presenting an opening for the reception of an implement to lock said valve-lifter against rotation.

6. A valve mechanism comprising, in combination, a puppet valve, a valve-lifting cam, a normally rotatable valve-lifter actuated by said cam, rotatable adjusting means carried by said valve-lifter, and a valve-lifter guide, said valve-lifter and guide being provided with generally radial surfaces adapted to receive between them an implement to lock said valve lifter against rotation.

7. In a tappet valve-actuating mechanism of the class in which the tappet rotates and reciprocates, the combination of a tappet having a screw and nut for effecting axial adjustment and means to lock said tappet against rotation preparatory to making such adjustment, said means comprising a member provided with an opening, and a key received in said opening and mounted to slide into and out of engagement with said tappet.

8. In a tappet valve-actuating mechanism of the class in which the tappet rotates and reciprocates, the combination of a tappet having a screw and nut for effecting axial adjustment and means to lock said tappet against rotation preparatory to making such adjustment, said means comprising a member provided with an opening having two faces on opposite sides of said tappet, and said tappet being provided with two corresponding faces on opposite sides thereof, and a generally U-shaped key having two arms adapted to be received between the faces of said tappet and the faces of said opening.

9. In a tappet valve-actuating mechanism of the class in which the tappet rotates and reciprocates, the combination of a tappet having a screw and nut for effecting axial adjustment and means to lock said tappet against rotation preparatory to making such adjustment, said means comprising a tappet guide provided in its outer end with a diametrical groove having two faces on opposite sides of said tappet, and said tappet being provided with two corresponding

faces on opposite sides thereof, and a generally U-shaped key having two arms adapted to be received between the faces of said tappet and the faces of said opening.

5 10. In a tappet valve-actuating mechanism of the class in which the tappet rotates and reciprocates, the combination of a tappet having a screw and nut for effecting

axial adjustment and means to lock said tappet against rotation preparatory to making such adjustment, said means comprising the members 14 and 24. 10

In testimony whereof, I have signed my name to this specification.

FRANS G. ALBORN.
